UNITED STATES PATENT OFFICE.

LOUIS DOVELL, OF NEWARK, NEW JERSEY.

DESIGN FOR A MUCILAGE-BOTTLE.

Specification forming part of Design No. 5,234, dated August 29, 1871.

To all whom it may concern:

Be it known that I, LOUIS DOVELL, of Newark, New Jersey, have invented and produced a new and original Design for Mucilage-Bottles, of which the following is a specification:

The drawing hereto annexed represents perspective views of this design.

A designates mucilage-bottles made in the form of a shoe, the neck or mouth of which is made with rounded edges, upon which the cap of the brush is placed.

What I claim is—

The shape or conformation of the mucilage-bottle, as herein shown and set forth.

LOUIS DOVELL.
